LATHER MIXING MACHINE

Ralph E. Switzer, Detroit, Mich., assignor to Morris B. Holmberg, Minneapolis, Minn.

Application June 20, 1955, Serial No. 516,458

11 Claims. (Cl. 299—83)

This invention relates to lather forming machines.

An object of my invention is the provision of a new and improved lather machine of relatively simple and inexpensive construction and operation which is well adapted for home use in the production of shaving lather.

Another object of my invention is to provide a novel lather mixing machine wherein the lather-forming brush, which agitates the soap and water and collects lather therein is wiped of lather which is then directly discharged for use.

Still another object of my invention is to provide an improved lather mixing machine wherein the lather formed and wiped from the rotating agitating brush is positively forced outwardly of the machine by action of the brush bristles.

A further object of my invention is the provision of a new lather mixing machine which permits the employment of a common type of bar shaving soap in the production of lather and which produces substantially only the amount of lather desired for immediate use when the machine is operated.

A still further object of my invention is the provision of a lather mixing machine wherein a single control renders the machine operative by controlling both the agitating and lather forming brush and the water supply necessary to the formation of lather.

These and other objects and advantages of my invention will more fully appear from the following description made in connection with the accompanying drawings wherein like reference characters refer to the same or similar parts throughout the several views and in which:

Fig. 1 is a perspective view of the lather mixing machine;

Fig. 2 is a cross section view taken on a vertical plane longitudinally through the invention substantially in a plane indicated at 2—2 in Fig. 1 and having portions of the brush broken away for sake of clarity;

Fig. 3 is a section view taken on a vertical plane substantially at 3—3 as shown in Figs. 1 and 2;

Fig. 4 is a detail section view taken along a broken horizontal line and looking upwardly as indicated at 4—4 in Fig. 2, and having the brush removed for clarity;

Fig. 5 is a detail section view taken on a vertical plane substantially at 5—5 of Fig. 3; and

Fig. 6 is a detail section view similar to Fig. 4 and showing another form of the invention.

The invention as shown in the drawings includes a housing or body member 10 which, in the form shown, is constructed of metal but may be formed of any other suitable rigid material. The housing 10 is stream-lined to present an exceedingly pleasing appearance for household use. A cover member 10a forming a part of the body member 10 is detachably secured at the rear portion thereof. In the upper portion of the housing 10 is formed a receptacle 11 for containing a supply of water for use in the lather mixing machine. A receptacle cover 11a is removably mounted on the housing 10 to enclose the receptacle 11. An enlarged interior chamber 12 is formed within the housing 10 and is of a substantially cylindrical shape defined by a peripheral wall surface 13 and by an end surface 14. The inner end of the chamber 12 is closed by a removable plate 15 which provides the other end defining surface 16 of the chamber 12. The

2

substantially cylindrical chamber 12 comprising the lather mixing compartment is provided with a lather discharge opening 17 which communicates through the end wall surface 14 and through a suitably formed spout 18 which projects outwardly from the housing 10 and may be formed integrally thereof.

As best seen in Figs. 2, 3 and 4, an elongated shoulder surface or ledge 19 is formed in the body member 10 and protrudes inwardly from the outer peripheral surface 10 which defines the chamber 12. The ledge 19 extends from one end of the chamber 12 to the other end thereof and is generally spirally disposed. The ledge 19 and the peripheral wall surface 13 defining the chamber 12 cooperate to form a lather collecting and discharging groove which is substantially co-extensive with the lather discharge opening 17 which extends through spout 18. As best seen in Fig. 4, one end 19a of ledge 19 is disposed closely adjacent the lather discharge opening 17 and at one side thereof and the inner end 19b of ledge 19 is 20 arcuately spaced from the outer end 19a thereof.

Means are provided for supplying soap into the chamber 12, and in the form shown such means include an enlarged opening 20 which extends through the body member 10 and through the peripheral wall surface 13 to communicate with the interior chamber 12. Opening 20 is, in the form shown, of substantially circular shape and is of sufficient size to accommodate a conventional bar 21 of shaving soap. The body member 10 has internal threads 22 provided at the outer end of the soap-receiving opening 20, and a suitable retaining cap 23 having an externally threaded portion 24 is threadedly mounted within the opening 20 for retaining the bar 21 of soap therein. Suitable means are provided for resiliently urging the bar 21 of soap inwardly of the chamber 12 and in the form shown comprises a compression spring 25 which is mounted in the cap 23 and which also engages a disc 26 which is disposed in the opening 20 for forcing the soap inwardly.

Means are also provided for introducing water into the chamber 12 to be mixed with the soap for forming lather and in the form shown, a water inlet opening 27 communicates between the water storage receptacle 11 and interior chamber 12 and a valve element 28 is shiftably mounted in the opening 27 to control the flow of water therethrough. Valve element 28 is normally biased to closed position and may be opened to permit water to flow from the receptacle 11 by gravity downward into the chamber 12. Valve element 28 is controlled by a push lever 29 which is slidably mounted in a suitable aperture 30 in body member 10 and which is attached to a rigid interconnection or shaft 31 which extends through a suitable opening 32 in body member 10 and connects to an actuating or connecting element 33. The connecting element 33 is connected to the valve element 28 and for operating the same when the push lever 29 is pushed inwardly of the body member 10. The spring 34 which is disposed in the bore 30 normally urges the push member 29 to its outward position, and the connecting element 33 limits the outward movement thereof.

Means are provided in the lather mixing chamber 12 for agitating the soap and water introduced therein for forming lather and in the form shown, such means comprise a rotary brush having radially disposed bristles which extend into proximity with the peripheral wall surface 13 for thoroughly mixing the water and soap supplied 65 into the chamber 12. The rotary brush 35 is journaled in suitable bearings 36 and 37 respectively mounted in the body member 10 and in the closure plate 15. As best seen in Figs. 2 and 3, the bristle end portions of the brush 35 engage and pass over the ledge 19 when the brush 35 is rotated in the direction of arrow D to be wiped of lather thereby.

The outer end portion 19a of ledge 19 is arcuately spaced from the inner end portion 19b thereof in the direction of travel of the bristle end portions of brush 35, which is indicated by the direction of arrow D.

Suitable means are provided for rotating the agitating brush 35 and in the form shown, such means include a friction disc 38 which is affixed to the rotary shaft 39 of brush 35 which extends through the plate 15 and the bearing 37. The friction disc 38 may be constructed of any suitable material and in the form shown, is constructed of a firm but resilient rubber. The means for driving the brush 35 also includes an electric motor indicated in general by numeral 40 which may be of any suitable type and in the form shown, includes a single phase shaded pole induction type motor having a laminated field member or stator 41 upon which is mounted a suitable field coil 42 which is retained by rigid members 43. Motor 40 is supported from the body member 10 and is connected thereto by suitable frame elements 40a which are connected to the stator 41 as by screws 40b and to the body member as by screws 40c. Motor 40 also includes a rotor 44 suitably mounted in bearings 45 which is supported from the stator 41. The rotor 44 is connected to the output spindle 46 which engages the outer peripheral surface of the friction element 38 for driving the same.

Spindle 46 and friction disc 38 provide an extremely simple and inexpensive speed reducing device between the motor 40 and the brush 35. Because of the employment of this unique speed reducing device the motor 40 may be of an extremely simple and inexpensive construction.

Suitable switch means for controlling operation of the motor 40, such means may comprise any suitable switching device connected in one side of the power supply for motor 40, and in the form shown such means include a microswitch 47 which is suitably mounted as on the rigid retainer members 43 adjacent the shiftable actuator 33 to be operated with shifting thereof. Microswitch 47 is of a conventional type and includes a push button 48 which is engaged by the actuator or connecting element 33 when the same is shifted by operation of the push lever 29.

In the form of the invention shown in Fig. 6 the construction of the lather machine is substantially identical to that shown in Figs. 1 through 5. The housing of body member 50 has a lather mixing chamber 51 formed therein, a discharge spout 52 having a discharge opening 53 communicating therethrough to the chamber 51, a soap bar opening 54 communicating through the peripheral chamber wall for introducing soap into chamber 51 and a threadably removable cap 55 for retaining the soap bar 56 in chamber 54 and urging the same inwardly toward the chamber 51. In the form of the invention shown in Fig. 6, a plurality of ledges 57, 58 and 59 are formed in the body member 50 and protrude inwardly into the chamber 51 in a manner substantially identical to that of ledge 19 in the form of the invention disclosed in Figs. 1 to 5. The ledges 57-59 extend generally longitudinally of the cylindrical lather mixing chamber 51 and are spirally disposed with respect to the chamber. The outer end portions 57a, 58a and 59a of the ledges are arcuately spaced from the inner end portions 57b, 58b and 59b thereof in the direction of travel indicated by arrow E, of the brush bristles. The ledge 57 will protrude inwardly into the chamber farther than the ledges 58 and 59 and the ledge 58 will protrude inwardly into the chamber farther than will ledge 59 from the peripheral chamber wall.

Operation

In the operation of the lather mixing machine, it will be placed in a convenient location as in the bathroom of a house adjacent the sink where shaving is usually done. The receptacle top 11a may be removed to permit the pouring of a supply of water into the receptacle 11. The spring 25 will resiliently urge the bar of soap inwardly

toward the chamber 12 so as to supply the necessary soap for forming lather.

When the push lever 29 is pushed as by the thumb of a person's hand, the fingers of the hand may be conveniently placed below the spout 18 to collect the lather discharge through the opening 17. When the push lever 29 is pushed inwardly to dotted position B thereof the actuator 33 is also shifted to dotted position B to engage the microswitch push button 48 and start the motor. 10 When the motor is started, the brush 35 will revolve in the form shown in the range of approximately 180 to 200 R. P. M. in the direction of arrow D. Substantially 15 simultaneously with the starting of motor 40, the valve element 28 will be shifted into the dotted position B thereof to open the water inlet 27 and permit water to pass from the receptacle 11 into the lather mixing chamber 12.

The rapidly rotating bristles of brush 35 will, as best shown in Fig. 3, engage the inner end of the soap bar 20 21 and thereby carry small portions of soap into the chamber wherein the water which has been supplied will be picked up by the rapidly rotating brush and be vigorously agitated with the soap to form a lather. The outer end portions of the brush bristles will engage and pass across 25 the ledge 19 and will be wiped thereof of soap lather carried thereby. The lather is thereupon collected on ledge 19 for discharge through the opening 17 in spout 18. Because the ledge 19 is substantially spirally disposed with relation to the peripheral wall of the chamber 30 12 and with respect to the outer periphery of the brush 35, the lather collected on ledge 19 will be positively forced and urged by the brush bristles from the inner edge portion 19b of ledge 19 toward the outer edge portion 19a thereof and outwardly of the discharge opening 35 17. The lather formed by the agitating brush 35 will thereby be discharged immediately after the lather has formed and substantially all of the lather formed during 40 rotation of the brush is discharged along ledge 19 and in the groove formed thereby in cooperation with the peripheral wall surface 13.

When the push lever 29 is released, the spring 34 urges it outwardly again to the full line position shown and the actuator 33 releases the microswitch 47 and causes the motor to stop substantially with the stopping of motor 40. The valve element 28 is shifted back into seated position to close the water inlet 27 and thereby preclude entrance of more water into the lather-forming chamber 12. The brush 35 will cease rotation when motor 40 has stopped and the discharge of lather through the opening 30 35 17 will cease substantially immediately when the rotating brush 35 is stopped.

The operation of the form of the invention shown in Fig. 6 is substantially identical to that shown in Figs. 1 to 5. In the form of the invention shown in Fig. 6 the brush bristles will be thoroughly wiped a plurality of times by the plurality of ledges 57-59. Because of the plurality of ledges, there will be somewhat more agitation of the bristles due to their passing over the ledges in succession as the brush is rotated.

It will be seen that I have provided a new and improved lather mixing machine wherein the rapidly rotating brush agitates the soap and water introduced into the lather forming chamber and then positively drives the lather outwardly of the mixing chamber through the discharge opening.

It should also be noted that I have provided a novel lather mixing machine wherein the lather discharged is wiped from the agitating bristles which carry a substantial supply of lather while rotating and wherein the discharge of lather is substantially immediately stopped when the brush stops revolving.

It will, of course, be understood that various changes may be made in the form, detail, arrangement and proportion of the parts without departing from the scope of my

invention which consists of the matter described herein and set forth in the appended claims.

What is claimed is:

1. A lather machine comprising a body member defining an enlarged chamber, means for introducing soap and water into said chamber, a rotary brush mounted within said chamber for movement in close proximity with the body member for agitating the soap and water therein and forming lather, said body member also having a wiping ledge extending inwardly of said chamber and engaging the bristles of said brush for wiping the lather therefrom, said body member having a lather outlet therein adjacent said ledge for discharging the lather collected thereon, and means for rotating said brush.

2. A lather machine comprising a body member having an enlarged interior chamber defined by an interior wall surface, means for introducing soap and water into said chamber, a rotary brush mounted within said chamber for movement in close proximity with the wall surface for agitating the soap and water and forming lather, a wiping ledge extending inwardly of the chamber from said surface and defining therewith a groove, a lather outlet in said body member communicating with said chamber and co-extending with said groove for discharging lather collected thereon, said brush having bristles with end portions, said bristle end portions engaging and passing over the ledge to be wiped thereby, and power means for rotating said brush, whereby lather will be formed in said chamber and collected in said bristles which are wiped on said ledge.

3. A lather machine comprising a body member having an interior wall surface defining a large interior chamber, a ledge secured to said body member and protruding inwardly of the chamber from said interior wall surface and cooperating with said surface to define a lather collecting groove, means for introducing soap and water into said chamber, a brush mounted in said chamber for continuing movement for agitating the soap and water and forming lather, the bristles of said brush engaging and moving transversely across said ledge to be wiped thereby, said body member having a lather discharge opening therein communicating with said chamber and co-extending with said groove for discharging lather collected thereon as said bristles move thereacross, and powered means for moving said brush.

4. A lather machine comprising a body member having an enlarged and substantially cylindrical chamber formed therein and defined by a peripheral interior wall surface, an elongated ledge secured to said body member and extending generally longitudinally of said chamber and projecting inwardly thereof from said peripheral surface, means for introducing soap and water into said chamber, a rotary brush mounted within said chamber and having radially disposed bristles extending into proximity with said peripheral wall surface for agitating the soap and water and forming lather, said bristles engaging and passing over said ledge to be wiped of lather thereby, said body member having a lather discharge opening communicating with said chamber and being disposed adjacent said ledge for discharging lather collected thereon, and means for driving said rotary brush.

5. The structure recited in claim 4 wherein said ledge and said peripheral wall surface define a groove for discharging lather therethrough, and wherein said lather discharge opening is disposed in co-extending relation with said groove, said groove having an outer end portion disposed adjacent said discharge opening and having an inner end portion, and said ledge being generally spirally disposed on said peripheral surface so as to arcuately space the outer end portion of said groove from the inner end portion thereof in the direction of rotation of said brush, whereby the brush will be wiped of lather by said ledge and will force the lather outwardly through said discharge opening.

6. The structure recited in claim 2 and including a

75

single control for substantially simultaneously operating said brush driving means and for introducing water into said chamber, whereby water is supplied into the chamber for forming lather when said brush is rotated and the supply of water is cut off when said brush is stopped.

5 7. The structure recited in claim 2 wherein said body member has an opening communicating with said chamber adjacent the ends of the rotating brush bristles therein for carrying a bar of soap to be engaged by said bristles for the formation of lather, and means urging such a bar of soap inwardly of the chamber into engagement with said brush.

10 8. A lather machine comprising a body member having an enlarged and substantially cylindrical interior chamber defined by an inwardly facing peripheral wall surface, a ledge protruding inwardly of said surface and defining therewith a lather collecting and discharge groove, said ledge extending generally spirally from one end of said chamber to the other end thereof, said body member having a lather discharge opening formed therein and extending through the end of said chamber in substantially end to end relation with said groove, and said body member having an opening communicating through the peripheral wall surface of said chamber for carrying a bar of soap, means for urging such a bar of soap inwardly of said chamber, and means for introducing water into said chamber, a rotary brush mounted within said chamber and having radially disposed bristles extending into proximity with said wall surface and engaging and being wiped by said ledge, said ledge being disposed to cause said bristles to force the lather collected thereon outwardly through said discharge opening, and means for rotating said brush.

15 9. A lather mixing machine comprising a body member having an enlarged and substantially cylindrical chamber formed therein and defined by a peripheral interior wall surface, means for introducing soap and water into said chamber, a rotary brush mounted within said chamber and having radially disposed bristles extending into proximity with said peripheral wall surface for agitating the soap and water and forming lather, a plurality of elongated ledges protruding inwardly of said chamber from said peripheral surface and extending generally longitudinally of the chamber, said bristles engaging and passing over said ledges to be wiped of lather thereby, and said body member having a lather discharge opening communicating with said chamber and disposed adjacent the ends of said ledges for discharging lather collected thereon, and means driving said rotary brush.

20 10. The structure recited in claim 9 wherein said separate ledges protrude inwardly of said chamber different distances from said peripheral surface and wherein said ledges are constructed and arranged to cause the brush bristles when passing thereover to positively drive the lather collected on the ledges outwardly through said discharge opening.

25 11. A lather machine comprising a body member defining an enlarged chamber, means for introducing soap and water into said chamber, a rotary brush mounted within said chamber for movement in close proximity with the body member for agitating the soap and water therein and forming lather, said body member also having a wiping ledge extending inwardly of said chamber and engaging the bristles of said brush for wiping the lather therefrom, said body member having a lather outlet communicating with said chamber, powered rotary means for rotating said brush including a motor and including a speed reducing device interposed between said motor and said brush.
